(57) **CLAIM**

We claim the ornamental design for an information handling system articulating display stand, as shown and described.

DESCRIPTION

FIG. 1 is a front perspective view of the information handling system articulating display stand comprising the present invention;

FIG. 2 is a front elevation view thereof;

FIG. 3 is a rear elevation view thereof;

FIG. 4 is a right side view thereof;

FIG. 5 is a left side view thereof;

FIG. 6 is a top view thereof;

FIG. 7 is a bottom view thereof;

FIG. 8 is a rear perspective view thereof;

FIG. 9 is a left side environmental view thereof in a raised position; and,

FIG. 10 is a left side environmental view thereof in a lowered position.

Broken lines shown in the drawings illustrate portions of the information handling system articulating display stand, and form no part of the claimed design.

1 Claim, 10 Drawing Sheets
